Application August 10, 1938, Serial No. 224,066

7 Claims. (Cl. 170—163)

(Granted under the act of March 3, 1883, as
amended April 30, 1928; 370 O. G. 757)

This invention relates to variable pitch propellers and impellers of the pusher or puller type, and it has for its principal object the provision of a propeller of the character indicated in which the pitch of the blades may be altered by hydraulic means operated by the drive shaft while the vessel pump or turbine is in operation.

With these and other objects in view, as well as other advantages that may be incident to the use of the improvements, the invention consists in the parts and combinations thereof herein-after set forth and claimed, with the understanding that the several necessary elements constituting the same may be varied in proportion and arrangement without departing from the nature and scope of the invention, as defined in the appended claims.

In order to make the invention more clearly understood, there are shown in the accompanying drawings, means for carrying the invention into practical use, without limiting the improvements in their useful application to the particular construction, which, for the purpose of explanation, have been made the subject of illustration.

In the accompanying drawings:

Fig. 1 is a longitudinal sectional view through a propeller hub embodying the invention;

Fig. 2 is a longitudinal sectional view through the hydraulically operated pitch changing mechanism;

Fig. 3 is a view partly in elevation and partly in transverse section taken on line 3—3 of Fig. 2;

Fig. 4 is a fragmentary detail view of the connection between the manually operable lever and the valve operating cams;

Fig. 5 is a fragmentary view partly in elevation and partly in transverse section taken on line 5—5 of Fig. 2 and illustrating the fluid pressure control valves;

Fig. 6 is a similar view showing the valves in another position;

Fig. 7 is a fragmentary transverse sectional view taken on line 7—7 of Fig. 2; and

Fig. 8 is a similar view taken on line 8—8 of Fig. 2 and illustrating the device for indicating the pitch of the propeller blades.

Referring to the drawings and particularly to Fig. 1 thereof, a variable pitch propeller of the pusher type constructed in accordance with the invention is shown as comprising a hub 10 formed with a forward portion 11 and an after portion 12 secured together and to a collar 13 formed integrally with the after section 14a of a multipart drive shaft by longitudinally extend-

ing bolts 15. The bolts 15 are formed with reduced threaded extremities 16 at each end, the forward extremities passing through a packing ring 17 which is secured in position thereby in abutting contact with the collar 13, thus preventing leakage at this point. The after extremities 16 of the bolts 15 pass through a flange 18 formed on a hollow stream lined hub cap 19 and is secured thereto in abutting contact with after portion 12 of the hub by nuts 20. Leakage at this point is prevented by a grease ring 21 which is secured to the hub cap by screws 22.

The portions 11 and 12 of the hub are formed with semicircular complementary recesses 23 in which the root portions 24 of a plurality of propeller blades 25 are mounted for rotary adjustment about radially extending axes. Each of the blades 25 is formed with a collar 26 adjacent its root 24 which seats within a correspondingly shaped recess formed in the portions 11 and 12 of the hub, thus reinforcing the blade and affording lateral and longitudinal stability thereto. The blades are each maintained against radial displacement by means of a collar 27 formed on the inner end of the root 24 and which is disposed within a longitudinal slot 28 formed in the portions 11 and 12 of the hub and a centrally disposed block 29 fixed to the shaft 14 by means of a key 30.

The blades 25 may be rotated a limited amount about their radial axes by means of a quill or torsion shaft 31 which extends coaxially through the drive shaft 14a and is rotatable therein. A bevel pinion 32 is fixed to the rear end of the quill shaft 31 and meshes with a segmented gear 33 provided on a ring 34 which is mounted on the collar 27 for rotary adjustment by means of key pins 35. Although the bevel gear 32 meshes with each of the segmental gears 33 so as to cause the propeller blades 25 to turn in unison when the pitch thereof is altered, additional means is provided to prevent binding of the parts which may be caused by infiltrations of sand and the like. This consists of an idle bevel gear 36 which is rotatably mounted on a reduced portion 37 of the block 29 for intermeshing engagement with segmental bevel gears 38 formed on the rings 34 opposite to the segmental gears 33. The construction hereinabove described is the subject of a co-pending application, Serial No. 224,068, filed August 10, 1938, now Patent No. 2,208,602.

The section 14a of the drive shaft is connected with the forward section 14b thereof through the instrumentality of a hydraulically operated mechanism which rotates the quill shaft 31 to alter

the pitch of the propeller blades and which will now be described. The section 14b of the drive shaft is formed with an annular flange 39 which is connected with a flange 40 formed on one end of a cylindrical housing 41 by means of a plurality of bolts 42 which pass through a series of circular plates 43, 44, 45 and 46 disposed therebetween and which are securely clamped together thereby for rotation in unison. The opposite or rear end of the housing 41 is also formed with a flange 47 which is connected with a collar 48 keyed to the section 14a of the drive shaft, by means of bolts 49 which pass through a ring member 50 and a two part collar 51 disposed therebetween, the collar 48 transmitting rotary motion to the section 14a and the two part collar 51 being formed with an internal annular shoulder 52 for engagement with an annular channel formed in the section 14a so as to prevent endwise movement of the parts. The elements are thus tied together for movement as a single unitary mass but are made separately for convenience in manufacture and assembly. Fixed to the forward end of the quill shaft 31 by means of key screws 53 is a clutch member 54 which is formed with a plurality of circumferentially arranged integral splines 55 for interlocking engagement with corresponding grooves formed in a ring 56. This ring carries a plurality of piston vanes 57 at spaced intervals around its outer circumferential surface which extend into spaces between coacting fixed vanes 58 (Fig. 7) provided at intervals around the inner circumferential surface of the ring 50, there being sufficient space between the vanes 57 and 58 to permit the clutch member 54 and quill shaft 31 to turn a limited amount. Leakage past the vanes 57 is prevented by suitable piston bars 59 mounted in slots formed therein and shaped to slidably receive them and spring pressed outwardly against the inner circumferential surface of ring 50. This structure functions as a cylinder and rotary piston.

The forward face of the clutch member 54 is formed with a plurality of clutch teeth 60 for engagement between similar clutch teeth on the opposed face of a plunger 61 which is splined as at 62 for axial sliding movement in a correspondingly splined ring 63 fixed in the rear end of the cylindrical housing 41. The plunger 61 is guided in its movement by a stud 64 engageable with a socket formed in the forward end of the quill shaft 31 and is provided with a forwardly extending stem 65, the extremity of which is fixed in a follower plate 66. The plunger 61 is urged rearwardly and its teeth into engagement with the teeth of the member 54 so as to prevent the rotation of the quill shaft 31, as will presently be described, by means of a coil spring 67. This spring bears against the plunger 61 and a seat 68 formed on a housing 69 which encloses the spring and is formed with a flange 70 at its rear end which is fixed to the rear end of the cylindrical housing 41. The plunger 61 is at times forced forwardly against the action of the coil spring 67 so as to disengage its teeth from those of the member 54, by means of fluid under pressure introduced into a metallic bellows 71 interposed between the follower plate 66 and the flange 70 of the spring housing 69.

The fluid, preferably oil, through which power is transmitted to the operating instrumentalities of the mechanism is forced through the system by means of a gear pump which comprises a plurality of gears 72 which are journaled on stud shafts 73 carried by the plate 43 for rotation with-

in recesses 74 (Fig. 2) formed in the adjacent plate 44. The teeth of the gears 72 are ground to conform closely to the walls of the recesses 74 to provide a substantially oil tight fit and mesh with a single internal ring gear 75 mounted for relative rotation on the outer circumference of the plate 44 between the plates 43 and 45. The teeth of the ring gear 75 also fit closely the circumferential surface of the plate 44 so as to minimize the leakage of oil therebetween in the manner of a gear pump. The leakage of oil between the sides of the ring gear 75 and the plates 43 and 45 is prevented by sealing rings 76 carried by these plates for engagement with grooves formed in the sides of the ring gear. The outer circumference of the ring gear 75 is grooved to receive a brake band 77 which may be actuated by any suitable means to retard or stop the rotation of the ring gear 75 so as to cause the rotation of the revolving gears 72 to pump fluid through the system. 20

Each of the gears 72 constitutes an oil pump in itself but is in fluid communication with the other gears so that they all function in unison to force oil through a plurality of parts and passages, presently to be described, in order to rotate the quill shaft 31 in opposite directions when it is desired to alter the pitch of the propeller blades. Associated with each of the gears 72 are two valve units 78 and 79 each comprising a sleeve valve member 80 mounted in a radially extending bore 81 formed in the adjacent plate 46 and provided with a stem 82 having a conical head 83 at its outer end. The sleeve 80 is urged outwardly by a coil spring 84 interposed between a shoulder 85 of the bore and the head 83. The valves 78 and 79 are alternately depressed by means of oppositely inclined cam blocks 86 and 87 which are fixed to a ring 88. This ring is mounted for longitudinal sliding movement on an annular slide 89 fixed to the forward flange 40 of the housing 41 and is provided with a plurality of stop and guide pins 90 for engagement with longitudinally extending slots 91 formed in the slide 89. The ring 88 and the cam blocks 86 and 87 carried thereby may be shifted longitudinally in order to actuate the valve units 78 and 79, by means of a yoke 92 pivotally mounted on a fixed base, as at 93, and provided with an operating handle 94. This yoke is pivotally connected by bolts 95 at diametrically opposed points to a two-part annular shoe 96 which is engageable with an annular groove 97 formed in the outer circumference of the ring 88. 35

When the ring 88 and the cam blocks 86 and 87 occupy the positions shown in Fig. 2, and the drive shaft is rotating in the direction shown by the arrows in Fig. 3, the gears 72 will revolve bodily about the axis of the drive shaft, rotating the ring gear 75 with them about said axis. If the brake band 77 is now tightened the rotation 60 of the ring gear 75 will be slowed down or stopped, thus causing the revolving gears 72 to also rotate about their own axes in the direction indicated by the arrows in Fig. 3. This will cause them to draw oil from passageways 98 in the plate 45 65 (Fig. 2) and force it into passageways 99 formed in said plate parallel to the passageways 98. From here the oil flows under pressure inwardly through radially extending passageways 100 in the plate 45 and thence rearwardly through a single 70 passageway 101 into the bellows 71. This will cause the bellows to expand and move the member 61 of the clutch forwardly and its teeth out of interlocking engagement with the teeth 60 of its coacting member 54. As the pressure of the 75

oil builds up in the system it will next be transmitted from the radial passageways 100 rearwardly through ports 102 into an annular groove 103 formed in the rear face of the plate 45 and through ports 104 into the inner ends of the bores 81 of the valve units 78. From here the oil flows outwardly through the sleeve valve members 80, thence through port 105 provided therein and into an annular groove 106 formed in the forward face of the cylindrical housing 41 and thence through passageways 107 into chambers 108 between the vanes 57 and 58. The pressure of the oil in these chambers forces the vanes 57 in a counter clockwise direction, as viewed in Fig. 7, and rotates the ring 56, clutch member 54 and quill shaft 31 also in a counter clockwise direction so as to adjust the pitch of the propeller blades in one direction. This movement of the vanes 57 together with the suction produced by the gears 72 on the other side of the system displaces oil from the chambers 109 on the left hand sides of the vanes 57 and causes it to flow through passageways 110 in the housing 41 paralleling the passageways 107 therein and into radially extending passageways 111. The oil next flows forwardly through ports 112 into an annular groove 113 formed in the housing 41 concentric with the groove 106, thence through ports 114 into the inner ends of the bores 81 of the valve units 79, thence outwardly through elongated ports 115 in the sleeve valve members 80 and ports 115 provided in the plate 46 and into an annular groove 116 formed in the plate 45 concentric with the groove 103. The oil next flows through ports 117 into radially extending passageways 118 and thence through the passageways 98 to the suction side of the gears 72. Oil is supplied to the system to compensate for leakage from a sump or reservoir 119 formed in a tubular extension 120 of the housing 41 which communicates with one of the passageways 118 through a port 121. The rapid rotation of the parts maintains the system completely filled with oil under centrifugal action.

The pitch of the blades of the propeller is determined by the rotary displacement of the quill shaft 31 with respect to the main drive shaft and this is indicated visually by means of a stem 122 (Fig. 8) which is mounted for radial sliding movement in the drive shaft 14a and collar 51. This stem is urged inwardly by means of a coil spring 123 and is provided with a head 124 for engagement with a cam 125 provided on the quill shaft 31. When the amount that the stem 122 projects shows that the propeller blades are at the desired pitch the brake band 77 is released so that the parts may again rotate in unison without causing the gears 72 to pump oil. This will relieve the pressure within the bellows 71 and permit the coil spring 67 to move the clutch member 61 rearwardly so as to cause its teeth to mesh with the coating teeth of the clutch member 54 on the quill shaft 31. This locks the parts against any further relative rotation and maintains the propeller blades at the adjusted pitch.

If it is desired to adjust the pitch of the blades in an opposite direction the ring 88 is shifted to the left, as viewed in Fig. 2, so as to force the sleeve valve members 80 of the valve units 79 inwardly and permitting the sleeves of the valve units 78 to be moved outwardly by the coil springs 84. This will reverse the flow of the oil through the system and rotate the vanes 57, ring 56 and quill shaft 31 in a clockwise direction.

In the event that the operator fails to release

the brake band 77 when the propeller blade reaches the limit of its turning or pitch changing movement, breakage of the parts caused by excessive oil pressure is prevented by means of a safety valve mechanism 126 (Fig. 3). This mechanism comprises a valve member 127 of the poppet type which is mounted in a bore 128 formed in the plate 45 and urged towards its seat 129 by a coil spring 130 interposed between the valve member 127 and a screw cap 131 threaded into the outer end of the bore 128. The valve member 127 controls communication between a passageway 132 which communicates through a port 133 with the annular channel 103, and the bore 128 which communicates through a port 134 with the annular channel 116. If excess pressure should develop within the system, oil from the gear pumps 72 will flow through the radial passageways 100 thence through the ports 102 into the annular passageway 103, thence through the port 133 into the passageway 132 and unseat the valve 127 against the force of the spring 130. The oil will then flow past the valve member 127 and into the bore 128, thence through the port 134 into the annular channel 116, thence through the ports 117 into the passageways 118 and thence through the ports 98 back to the gear pumps 72 in a closed circuit. It will be noted that the pressure of the oil in the system will not be decreased by the opening of the safety valve 126 but will remain at a maximum value determined by the strength of the spring 130.

Operation

To summarize, the mechanism of this invention varies the pitch of a propeller by causing relative angular movement of a quill shaft with respect to a propeller shaft concentric therewith. This angular movement is effected hydraulically by the operation of a planetary gear pump which forces oil into a bellows, thus declutching a clutch which normally prevents relative angular movement of the two shafts, and also forces oil into alternate chambers of a series of chambers formed between adjacent faces of loosely intermeshed teeth, one set of which is formed on the circumference of the quill shaft and the other set of which is formed on the inner circumference of an extension of the hollow propeller shaft. The same pump simultaneously sucks oil from the remaining chambers of said series, thus forcing relative angular movement between the two shafts. Reversal of the flow of oil, sending it to the chambers formerly evacuated and evacuating it from the chambers formerly filled is accomplished by the positioning of sleeve valves which govern the connection of various oil passages to the suction and delivery sides of the oil pump. The positioning of the sleeve valves is governed by a ring-cam movable longitudinally of the shafts by manually operable means.

It will be understood that the above description and accompanying drawings comprehend only the general and preferred embodiment of the invention and that various changes in construction, proportion and arrangement of the parts may be made within the scope of the appended claims without sacrificing any of the advantages of the invention.

The invention described herein may be manufactured and/or used by or for the Government of the United States of America for governmental purposes without the payment of any royalties thereon or therefor.

We claim:

1. A variable pitch propeller comprising a main drive shaft, a hub carried by said shaft, a blade mounted on said hub for adjustable rotation about a radially extending axis to vary the pitch thereof, a quill shaft extending through and rotatable in said drive shaft and operatively connected with said blade for rotating the same about said axis, fluid pressure operated means for rotating said quill shaft, pump means operable by the rotation of said main drive shaft for operating said fluid pressure means and clutch mechanism also operable by said pump means for positively locking said drive shaft and said quill shaft against relative rotation to maintain said blade in its adjusted position.

2. A variable pitch propeller comprising a main drive shaft, a hub carried by said shaft, a blade mounted on said hub for adjustable rotation about a radially extending axis to vary the pitch thereof, a quill shaft extending through and rotatable in said drive shaft and operatively connected with said blade for rotating the same about said axis, fluid pressure operated means for rotating said quill shaft, a planetary gear pump operable by the rotation of said main drive shaft for operating said fluid pressure means and clutch mechanism also operable by said pump means for positively locking said drive shaft and said quill shaft against relative rotation to maintain said blade in its adjusted position.

3. A variable pitch propeller comprising a main drive shaft, a hub carried by said shaft, a blade mounted on said hub for adjustable rotation about a radially extending axis to vary the pitch thereof, a quill shaft extending through and rotatable in said drive shaft and operatively connected with said blade for rotating the same about said axis, fluid pressure operated means for rotating said quill shaft, pump means operable by the rotation of said main drive shaft for operating said fluid pressure means, valve means for controlling the direction of flow of fluid under pressure from said pump means to said fluid pressure operated means to reverse the direction of rotation of said quill shaft and the resulting pitch of said blade and clutch mechanism also operable by said pump means for positively locking said drive shaft and said quill shaft against relative rotation to maintain said blade in its adjusted position.

4. A variable pitch propeller comprising a main drive shaft, a hub carried by said shaft, a blade mounted on said hub for adjustable rotation about a radially extending axis to vary the pitch thereof, a quill shaft extending through and rotatable in said drive shaft and operatively connected with said blade for rotating the same about said axis, fluid pressure operated means for rotating said quill shaft, pump means operable by the rotation of said main drive shaft for oper-

ating said fluid pressure means, valve means for controlling the direction of rotation of said quill shaft and the resulting pitch of said blade, manually operable cam means for controlling the operation of said valve means and clutch mechanism also operable by said pump means for positively locking said drive shaft and said quill shaft against relative rotation to maintain said blade in its adjusted position.

5. A variable pitch propeller comprising a main drive shaft, a hub carried by said shaft, a blade mounted on said hub for adjustable rotation about a radially extending axis to vary the pitch thereof, a quill shaft extending through and rotatable in said drive shaft and operatively connected with said blade for rotating the same about said axis, fluid pressure operated means for rotating said quill shaft, pump means operable by the rotation of said main drive shaft for operating said fluid pressure means, clutch mechanism for releasably locking said quill shaft in its adjusted position, and fluid pressure means for releasing said clutch mechanism.

6. A variable pitch propeller comprising a main drive shaft, a hub carried by said shaft, a blade mounted on said hub for adjustable rotation about a radially extending axis to vary the pitch thereof, a quill shaft extending through and rotatable in said drive shaft and operatively connected with said blade for rotating the same about said axis, fluid pressure operated means for rotating said quill shaft, pump means operable by the rotation of said main drive shaft for operating said fluid pressure means, clutch mechanism interposed between said drive shaft and said quill shaft, spring means for yieldably urging said clutch mechanism toward engaged position, and an expansible bellows operable by fluid pressure for disengaging said clutch mechanism to permit the rotary adjustment of said quill shaft relative to said drive shaft.

7. A variable pitch propeller comprising a main drive shaft, a hub carried by said shaft, a blade mounted on said hub for adjustable rotation about a radially extending axis to vary the pitch thereof, a quill shaft extending through and rotatable in said drive shaft and operatively connected with said blade for rotating the same about said axis, fluid pressure operated means for rotating said quill shaft, pump means operable by the rotation of said main drive shaft for operating said fluid pressure means, and a centrally located reservoir rotatable with said drive shaft for supplying under centrifugal action fluid to said fluid pressure operated means and said pump means at points radially displaced from said reservoir.

ROBERT J. RUTHS.

HARRY L. DODSON.
